United States Patent Office

Des. 210,225

Patented Feb. 20, 1968

210,225

COCKTAIL TABLE

John B. Thorn, Lynchburg, and Andre Bus, Altavista, Va.,
assignors to The Lane Company Inc., Altavista, Va.,
a corporation of Virginia

Filed Apr. 10, 1967, Ser. No. 6,611

Term of patent 14 years

(Cl. D33—14)

The figure is a perspective view of the cocktail table of our new design, a view from a substantially diagonally opposite perspective would be substantially the same in appearance.

We claim:

The ornamental design for a cocktail table, as shown and described,
